Design N° 279

*J. Cox & Co. designs of
Joshua Crandall
Stove Design*

DES 279

Patented April 9, 1850

Ms. 179

A. Cox & Co. Assignees of
Joshua Crandall of Troy N.Y.
Letters Patent. No. 279. Dated April 9, 1850.

The Schedule referred to in these Letters Patent and making part of the same.

To all whom these presents shall come:

Be it known that I, Joshua Crandall of Troy, in the County of Rensselaer, and State of New York, have invented or produced a new and original design of Cooking Stove, which I call the "Queen of the City," and I do hereby declare that the following is a full, clear, and exact description of the same, reference being had to the annexed drawings, making a part of this specification, in which fig. 1. is a side elevation of the whole stove, and fig. 2. a view of the front plate with one door, and one removed.

My stove is in the usual form of a square, four boiler cooking stove; so shaped in its mouldings, and disposition of ornaments, as to constitute a new design and configuration of stove.

In the front there are two doors, fac. similes of each other, only one of which is represented in the drawing. The top and bottom of the stove, with the exception of the edges, which are formed of heavy mouldings, which project out beyond other parts of the stove, are plain.

The doors are bordered with mouldings, forming panels in the central part, which are elaborately ornamented with arabesque figures a. a. a.; the side of the stove is ornamented in like character, at b. b.

2

Des 2709

The stove is supported on three ornamented legs, as
represented at c. c.

What I claim as my new design, and desire to secure
by Letters Patent, is the design and configuration of the ornaments so disposed on the doors,
feet and other parts of the stove, constituting in combination a new design of stove, substantially the
same as herein described and represented.

Witnesses.
